UNITED STATES PATENT OFFICE.

CHARLES W. REYNOLDS, OF DETROIT, MICHIGAN, ASSIGNOR OF ONE-HALF
TO WILLIAM H. BURTENSHAW, OF SAME PLACE.

PROCESS OF MANUFACTURING SHOES.

SPECIFICATION forming part of Letters Patent No. 299,421, dated May 27, 1884.

Application filed December 29, 1883. (No model.)

To all whom it may concern:

Be it known that I, CHARLES W. REYNOLDS, of Detroit, in the county of Wayne and State of Michigan, have invented a new and useful Improvement in Processes of Making Shoes, of which the following is a specification.

Figure 1 is a top plan view of an insole and the false insole. Fig. 2 is a plan view of the bottom of the shoe when ready for the sole, and Fig. 3 is a longitudinal central section through the shoe.

My invention consists in a novel method of making a sewed shoe, whereby I am enabled to use an insole too light to be used in shoes made in the ordinary manner, or to dispense with an insole entirely, thus making a very light and flexible shoe, as hereinafter pointed out, and specified in the claim.

A represents an insole made very light, not heavy enough to use in the ordinary method of construction, except where it is thickened at the heel by pieces pasted or tacked on.

B represents a piece of thin sole-leather, shaped as shown in the drawings, and wide enough to cover the space between the edges of the uppers when the shoe is lasted, which acts as a false insole. I usually bevel the edge of false insole B; but this may be omitted.

C represents the upper, and E the sole, of the shoe.

D represents a strip of leather, rawhide, or other suitable material, and d-e represent tacks used in process of manufacture.

My improved mode of manufacture is as follows: When the light insole A is to be used, the false insole B is lightly tacked onto the insole by tacks d, so that the insole A projects on all sides beyond the false insole B. The shoe is now drawn over a last having a metal sole, and the insole A is laid on the sole of the last with the false insole B against the last. The upper is now drawn over the insole and secured thereto by tacks e, which are driven through the strip D, the upper and lining, the insole A, the false insole B, and are turned over or clinched by the last. The ends of strip D are placed over the rear ends of the false insole D, (marked g,) and the strip thence follows the edges of the upper to the toe of the shoe, c, where the strip is doubled back and extends in a loop, b, to the heel of the shoe, being usually secured by a tack, f, as shown. The last is now withdrawn, the sole E placed

in position, and sewed to the upper and insole in the usual manner, the heel being left unsewed. When a steel or other shank is to be used, I prefer to fasten it to the inner surface of the sole E by pasting a thin piece of leather over it. The end g of the false insole B is now seized by a pair of pinchers, as shown in dotted lines in Fig. 3, and the false insole pulled out of the shoe, straightening the clinched ends of tacks e. The end b of strip D is now seized by a pair of pinchers and the strip pulled out, bringing with it the tack f and all the tacks e, when the heel may be nailed on and the shoe finished in the usual manner. This makes a shoe with a very flexible sole and of cheap construction. When the insole is to be entirely omitted, the false insole B is placed on the last, the uppers tacked onto it, as before, and the false insole and tacks removed in the manner hereinbefore described. While the shoe is being sewed, I bend a piece of spring-wire into approximately the form of the last, but larger, compress it, and slip it into the shoe, so that its expansion will distend the upper, which prevents the horn of the sewing-machine from catching in the lining, and also prevents the needle of the sewing-machine from engaging with that part of the lining which should be above the seam. A short heel-insole is put inside the shoe to hold the nails which fasten the heel, the heel nailed on, and I then put the ordinary sock-lining in the shoe.

What I claim as my invention, and desire to secure by Letters Patent, is—

The herein-described process in manufacturing a flexible shoe, consisting in placing upon the last a false insole, drawing the upper over the last, and tacking its edge to said false insole by a row of tacks, which first pass through a strip of rawhide or similar suitable material laid along the edge of said upper to the toe of the shoe, and thence doubled back and led to a point near the heel, then uniting the sole and upper in any usual manner, and then pulling out said false insole and said rawhide strip, substantially as shown and described.

CHARLES W. REYNOLDS.
